UNITED STATES PATENT OFFICE.

WILLIAM F. RICHARDSON, OF PORTSMOUTH, VIRGINIA.

WATER HEATER.

Application filed April 17, 1925. Serial No. 23,897.

To all whom it may concern:

Be it known that I, WILLIAM F. RICHARDSON, a citizen of the United States residing at Portsmouth, in the county of Norfolk and State of Virginia, have invented a new and useful Water Heater, of which the following is a specification.

This invention relates to water heating apparatus, one of its objects being to provide means whereby it becomes unnecessary to utilize a coil within a heating furnace in order to heat water designed for domestic purposes.

A further object is to provide a heater which can utilize either the water or steam of a heating system for the purpose of heating water for domestic use or can employ a gas burner or the like while the furnace is not in use.

Another object is to provide a water heater which can be easily installed and is very efficient in operation.

With the foregoing and other objects in view which will appear as the description proceeds the invention resides in the combination and arrangement of parts and in the details of construction hereinafter described and claimed, it being understood that changes in the precise embodiment of the invention herein disclosed may be made within the scope of what is claimed without departing from the spirit of the invention.

In the accompanying drawings the preferred form of the invention has been shown.

In said drawings,

Figure 1 is a central vertical section through the water heater, the same being shown connected to a furnace and to a domestic boiler.

Figure 2 is an enlarged section on line 2—2 Figure 1.

Referring to the figures by characters of reference 1 designates a furnace of the hot water type and Figure 2 designates an ordinary domestic boiler. The heater constituting the present invention is adapted to be connected both to the furnace and the boiler. This heater includes a drum 3 having a base 4 adapted to be supported in any suitable manner, and fitted within the base 4 is a burner 5 having a supply pipe 6 leading thereto. This burner is adapted to use gas as a fuel although it is to be understood that an oil burner may be employed under some conditions. The upper end of

the drum 3 has a hood 7 which is conical and provided with an outlet flue 8.

Extending longitudinally within the drum 3 at the center thereof is a flue 9 having flared ends 10 and 11. The lower flared end 11 extends to the lower margin of the drum 3 while the upper flared end 10 of the flue extends to the upper margin of the drum. Thus the flue, and its flared ends permit the free flow of hot combustion products upwardly through the drum to the outlet flue 8.

Arranged within the drum 3 is a sleeve 12 spaced from and concentric with the flue 9, this sleeve having a flared upper end 13 spaced from the flare 10 and extending to the wall of the drum 3. It also has a flared lower end 14 spaced from the flare 11 and extending to the wall of the drum. Flue 9 with its ends cooperates with sleeve 12 and its flared ends to provide a water jacket 15 which extends around the flue 9. A heating chamber 16 is also provided within the drum 3 and around sleeve 12. This chamber 16 is adapted to receive and deliver water or steam through pipes 17 which are connected to the hot water or steam pipes 18 of furnace 1. Consequently during the operation of the furnace 1 the water contained in the chamber 16 will be maintained at approximately the same temperature as that in the pipes and radiators of the heating system connected to furnace 1.

The domestic boiler 2 is connected, by pipes 19, to the upper and lower ends of the water jacket 15. Thus water admitted to the boiler 2 in the usual way will circulate through and be heated in the water jacket, the temperature thereof being raised by the hot water or steam supplied to chamber 16 from the pipes 18. As long as the heating system is in operation an ample supply of water for domestic purposes will be maintained in the boiler 2 as will be obvious. If, however, the use of the heating plant is stopped or else the temperature is so reduced that only a very low heat is maintained, the burner 5 can be used to raise the temperature of the water in the jacket 15. During the use of this burner the hot product of combustion will flow along the flared end 11 and into flue 9 and then outwardly through the hood 7 to flue 8. During its passage through the flue 9 and along the end 11, the products of combustion will

quickly raise the temperature of the parts contacted thereby and also correspondingly raise the temperature of the contents of the water jacket.

5 It will be apparent that by utilizing a domestic water heater such as described it becomes possible to provide an ample supply of water for domestic purposes at all times, the heating system connected to the furnace 10 1 being utilized during cold weather for heating the domestic water while the gas burner 5 is utilized during moderate and warm weather. The principle advantage of this construction is the elimination of water 15 coils which are liable to break in the fire box of the furnace and require the drawing of the fire during the coldest weather.

What is claimed is:

A domestic water heater including a 20 drum, a hood thereon having an outlet, a

central longitudinal flue having flared ends extending to the wall of the drum, a sleeve mounted within the drum and having flared ends extending to the walls of the drum, said sleeve and its ends being spaced from 25 the flue and its ends and cooperating therewith to provide a water jacket, there being a compartment surrounding the sleeve and out of communication with the water jacket, said compartment having an inlet and an 30 outlet, there being an inlet and an outlet to the water jacket, and a burner beneath the drum for directing products of combustion into the flared lower end of the flue.

In testimony that I claim the foregoing as my own, I have hereto affixed my signature.

WILLIAM F. RICHARDSON.
